UNITED STATES PATENT OFFICE.

JOHN A. HOLZAPFEL, OF JACKSON, MICHIGAN.

WRINGER FOR ANCHOR ROPES.

Application filed May 27, 1922. Serial No. 564,261.

To all whom it may concern:

Be it known that I, JOHN A. HOLZAPFEL, a citizen of the United States, residing at the city and county of Jackson, State of Michigan, have invented certain new and useful Improvements in Wringers for Anchor Ropes, of which the following is a specification.

This invention relates to a wringer for anchor ropes.

The main objects of this invention are:

First, to provide a wringer for anchor ropes which effectively removes the surplus water therefrom as the rope is hauled into the boat and at the same time is comparatively easy to operate.

Second, to provide a wringer for anchor ropes which may be readily applied to a row boat or the like and removed therefrom as occasion requires.

Third, to provide an improved device of the class described with which the rope may be easily engaged or disengaged as occasion requires.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a side elevation of my improved anchor rope wringer mounted upon the prow of a boat, the boat being shown conventionally.

Fig. II is a side elevation with the hinged pulley block plate open to show the manner of engaging and disengaging the rope.

Fig. III is a plan view of the base.

Fig. IV is a detail vertical section on a line corresponding to line 4-4 of Figs. II and III.

Fig. V is a detail vertical section on a line corresponding to line 5-5 of Fig. II.

Fig. VI is a vertical section on a line corresponding to line 6-6 of Fig. II.

In the drawing similar reference characters refer to similar parts throughout the several views and the sectional views are taken looking in the direction of the little arrows at the ends of the section lines.

Referring to the drawing, 1 represents the

prow of a boat. I provide a base plate 2 adapted to be mounted upon a boat, it being provided with screw holes 3 and with a downwardly projecting arm 4 having a hole 60 5 therein. At its front end this plate is provided with an eye 6 to which the painter rope may be attached. The base plate is provided with rearwardly facing sockets 7 and 8 and with a laterally opening slot 9. 65 The socket 8 is tapered to receive the rear lug 10 of the pulley block base 11. This base is also provided with a lug 12 adapted to be engaged with the front socket 7 and has a slot 13 which is aligned with the slot 70 9 when the parts are in engagement.

The pulley block has a fixed side member 14 and a hinged side member 15, the hinged side member being pivoted to the fixed side member at 16. The hinged side member has a 75 projection 17 which is adapted to close into the slot 9 and a projection 18 adapted to close in the space 19 between the sockets, thereby locking the pulley block to the base.

A relatively fixed wringer pulley 20 is 80 mounted on the pin 21 carried by the fixed side member 14, while a coacting movable wringer pulley 22 is carried by the swinging arm 23 pivoted at 24 on the fixed side member. A coiled spring 25 urges the wringer 85 pulley 22 towards the pulley 20. The guide pulley 26 is mounted on the pin 27 below and at the rear of the movable pulley so that a pull on the anchor rope 28 secures a wringing action thereon as it is drawn between the 90 pulleys 20 and 22. The pin 29 for the swinging pulley projects through the segmental slot 30 in the side member 14 and through the slot 31 in the side member 15. The slot 31 has an enlargement 32 at its rear 95 end to receive a head 33 of the pivot 29. The swinging arm 23 has an extension 34 at its lower end which projects through a hole 35 in the swing side member and has an arm 34 having a hole 36 therein adapted to receive a lock, as 37, thereby locking the swinging side member in closed position. By swinging this side member open the anchor rope plate may be engaged or disengaged and when locked it serves as a lock 105 not only for retaining the rope but also locks the pulley block to the base.

A laterally opening fixed jaw 38 is provided at the rear of the pulley 26 and a coacting pivot jaw 39 is mounted at 40 below 110 the jaw 38. A coiled spring 41 yieldingly urges the pivot jaw 39 toward the fixed jaw.

Thus arranged, the rope may be engaged and disengaged by lateral swinging of the rope. The jaw 38 is preferably provided with a flag staff socket 42. The spring 25 holding the pin 33 normally in the reduced portion of the slot holds the swinging side 18 in closed position.

With the parts thus arranged they are very efficient and at the same time are simple and economical to produce.

I have illustrated and described a very practical embodiment. I have not attempted to illustrate or describe other embodiments or adaptations as it is believed the disclosure made will enable those skilled in the art to which my invention relates to embody or adapt the same as may be desired.

Having thus described my invention, what I claim as new and desire to secure by Letters Patent, is:

1. In a device of the class described, the combination of a base plate having a laterally opening anchor rope slot at its front end and spaced rearwardly opening pulley block sockets, the rear socket being tapered, a pulley block comprising a base member having headed lugs engageable with said base plate sockets by a longitudinal movement and having a laterally opening slot aligned with said slot of said base plate, a relatively fixed pulley block side member, a swinging pulley block side member hinged to the upper edge of said fixed side member and provided with parts adapted to close into the anchor rope opening and between the sockets of said base plate to lock the pulley block thereto, said side members being provided with aligned segmental slots, 40 that of the swinging side member having an enlargement at its rear end, coacting wringer pulleys, one being mounted on said fixed side member above said anchor rope slot, a swinging supporting arm for the other wringer pulley pivotally mounted on said fixed side member and provided with a headed pulley journal disposed in said slots in said side members, a spring urging said arm yieldingly forward, and a guide pulley journaled on said fixed side member with its axis in a plane below that of the movable wringer pulley whereby the pull upon the rope exerts a wringing pressure thereon.

2. In a device of the class described, the combination of a base plate having spaced rearwardly opening pulley block sockets, the rear socket being tapered, a pulley block comprising a base member having headed lugs engageable with said base plate sockets by a longitudinal movement, a relatively fixed pulley block side member, a swinging pulley block side member hinged to the upper edge of said fixed side member and provided with a part adapted to close between the sockets of said base plate to lock the

pulley block thereto, said side members being provided with aligned segmental slots, that of the swinging side member having an enlargement at its rear end, coacting wringer pulleys, one being mounted on said fixed side member, a swinging supporting arm for the other wringer pulley pivotally mounted on said fixed side member and provided with a headed pulley journal disposed in said slots in said side members, a spring urging said arm yieldingly forward, and a guide pulley journaled on said fixed side member with its axis in a plane below that of the movable wringer pulley whereby the pull upon the rope exerts a wringing pressure thereon.

3. In a device of the class described, the combination of a base plate having a painter eye and a laterally opening anchor rope slot at its front end and a pulley block socket, a pulley block comprising a base member engageable with said socket having a laterally opening slot aligned with said slot of said base plate, a relatively fixed pulley block side member, and a swinging pulley block side member provided with a part adapted to close into the anchor rope opening to lock the pulley block to the base plate, coacting wringer pulleys, one being mounted on said fixed side member above said anchor rope slot, a swinging supporting arm for the other wringer pulley pivotally mounted on said fixed side member, a spring urging said arm yieldingly forward, a guide pulley journaled on said fixed side member below and at the rear of the movable pulley, a laterally opening fixed jaw at the rear end of said pulley block base member, and a coacting jaw within said fixed jaw, said fixed jaw having a flag staff socket on its upper side.

4. In a device of the class described, the combination of a base plate having a painter eye and a laterally opening anchor rope slot at its front end and a pulley block socket, a pulley block comprising a base member engageable with said socket having a laterally opening slot aligned with said slot of said base plate, a relatively fixed pulley block side member, and a swinging pulley block side member provided with a part adapted to close into the anchor rope opening to lock the pulley block to the base plate, coacting wringer pulleys, one being mounted on said fixed side member above said anchor rope slot, a swinging supporting arm for the other wringer pulley pivotally mounted on said fixed side member, a spring urging said arm yieldingly forward, and a guide pulley journaled on said fixed side member below and at the rear of the movable pulley.

5. In a device of the class described, the combination of a pulley block comprising a relatively fixed pulley block side member, a pivoted pulley block side member, said side members being provided with aligned segmental slots, that of the swinging side mem.

- ber having an enlargement at its rear end, coacting wringer pulleys, one being mounted on said fixed side member, a swinging supporting arm for the other wringer pulley 5 pivotally mounted on said fixed side member and provided with a headed pulley journal disposed in said slots in said side members, and a guide pulley journaled on said fixed side member with its axis in a plane below 10 that of the movable wringer pulley whereby the pull upon the rope exerts a wringing pressure thereon.
6. In a device of the class described, the combination of a pulley block comprising a relatively fixed pulley block side member, a pivoted pulley block side member, said side members being provided with aligned segmental slots, coacting wringer pulleys, one being mounted on said fixed side member, 15 a swinging supporting arm for the other wringer pulley pivotally mounted on said fixed side member, and a guide pulley journaled on said fixed side member with its axis in a plane below that of the movable wringer 20 pulley whereby the pull upon the rope exerts a wringing pressure thereon.
7. In a device of the class described, the combination of a pulley block comprising a relatively fixed pulley block side member, a pivoted pulley block side member, said side members being provided with aligned segmental slots, coacting wringer pulleys, one being mounted on said fixed side member, a swinging supporting arm for the other 25 wringer pulley pivotally mounted on said fixed side member, a guide pulley journaled on said fixed side member with its axis in a plane below that of the movable wringer pulley whereby the pull upon the rope exerts a wringing pressure thereon.
- 30 8. In a device of the class described, the combination of a pulley block comprising a relatively fixed pulley block side member, a pivoted pulley block side member, said side members being provided with aligned segmental slots, coacting wringer pulleys, one being mounted on said fixed side member, a swinging supporting arm for the other wringer pulley pivotally mounted on said fixed side member, a guide pulley journaled on said fixed side member with its axis in a plane below that of the movable wringer 35 pulley whereby the pull upon the rope exerts a wringing pressure thereon, a laterally opening fixed jaw at the rear end of said pulley block side members, a coacting pivoted jaw mounted within said fixed jaw, and a spring urging said pivoted jaw towards 40 said fixed jaw, said fixed jaw having a flag staff socket on its upper side.
- 45 9. In a device of the class described, the combination of a pulley block comprising a relatively fixed pulley block side member, a pivoted pulley block side member, coacting wringer pulleys, one being mounted on said fixed side member, a swinging supporting arm for the other wringer pulley pivotally mounted on said fixed side member, a spring urging said arm yielding forward, a guide pulley journaled on said fixed side member below and at the rear of the movable pulley, a laterally opening fixed jaw at the rear end of said pulley block base member, and a coacting 50 jaw within said fixed jaw, said fixed jaw having a flag staff socket on its upper side.
10. In a device of the class described, the combination of a pulley block comprising a base member, a relatively fixed pulley block 55 side member, and a swinging pulley block side member, coacting wringer pulleys, one being mounted on said fixed side member, a swinging supporting arm for the other wringer pulley pivotally mounted on said fixed side member, a spring urging said arm yielding forward, and a guide pulley journaled on said fixed side member below and at the rear of the movable pulley.
11. In a device of the class described, the combination of a pulley block, a pulley block side member, a pair of coacting wringer pulleys, one being mounted in a relatively fixed position, a swinging supporting arm for the other wringer pulley, a spring urging said movable pulley yielding toward the swinging pulley, and a guide pulley disposed at the rear of and in a plane below the axis of the swinging pulley.
12. In a device of the class described, the combination of a pulley block, a pair of coacting wringer pulleys, one of which is movably mounted relative to the other, and a guide pulley disposed at the rear of and below the movable pulley, all coacting for the purpose specified.

In witness whereof, I have hereunto set my hand and seal.

JOHN A. HOLZAPFEL. [L.S.]
